(57) **CLAIM**

The ornamental design for an air compressor panel for a vehicle panel as shown and described.

DESCRIPTION

FIG. 1 is a front view of an air compressor panel for a vehicle panel according to the new design.

FIG. 2 is a top view thereof.

FIG. 3 is a right-side view thereof.

FIG. 4 is a left-side view thereof.

FIG. 5 is a front left perspective view showing the air compressor panel for a vehicle panel in an installed configuration; and,

FIG. 6 is an enlarged front left perspective view showing the air compressor panel for a vehicle panel in an installed configuration.

The portions of the air compressor panel for a vehicle panel rendered in darker gray tones are claimed. The portions of the air compressor panel for a vehicle panel rendered in light gray in FIGS. 5 and 6 depict environmental subject matter and form no part of the claimed design.

1 Claim, 6 Drawing Sheets
